UNITED STATES PATENT OFFICE.

JOHN ROTHWELL AND CHARLES ROTHWELL, OF PHILADELPHIA, PA.

LOOM FOR WEAVING PILE FABRICS.

SPECIFICATION forming part of Letters Patent No. 257,517, dated May 9, 1882.

Application filed July 22, 1881. (No model.)

To all whom it may concern:

Be it known that we, JOHN ROTHWELL and CHARLES ROTHWELL, both of the city and county of Philadelphia, State of Pennsylvania, have made certain new and useful Improvements in Looms for Weaving Pile Fabrics, of which the following is a full, clear, and exact description, reference being had to the annexed drawings, making part hereof.

Our invention relates to a class of looms for weaving a pile-looped fabric, in the production of which fabric two series of warps are required, one for making the body, called the "body-warp," and one for making the loops, called the "terry-warp," the body-warp being weighted with more friction than the terry-warp. The loops are made by partially beating up certain picks of weft-thread, and afterward further beating up or driving home those picks in order to cause the terry-warp threads to be drawn off faster than the body-warp threads, and causing them to rise up from the body in loops. By means of a locking device hereinafter described this looping operation may be suspended at any desired moment and the loom made to weave plain cloth. The fabric thus woven is especially designed for towels, napkins, and other like fabrics to which it may be desired to give a looped body and a plain border.

Our improvement consists in the peculiar mechanical combinations of parts hereinafter described, and particularly pointed out in the claims.

To enable others skilled in the art of weaving looped fabrics and in the construction of looms to make and use our invention, we will now proceed to describe its construction and mode of operation.

In the drawings, Figure I is an inside elevation of the end of a loom having our improvements attached. Fig. II is a top view of such a loom. Figs. III and IV are a top view and side elevation, respectively, of our adjustable mechanism for operating the eccentric-bearing, the parts being disposed as they are when the loom is weaving a looped fabric. Fig. V is a similar view of said mechanism disposed as when the loom is weaving plain cloth. Figs. VI, VII, VIII are detached views, showing the construction of the eccentric-bearing. Fig.

IX is an elevation, showing the terry-lever, &c.

A is the frame of the loom, to which are attached the journal-boxes B, containing (Fig. VII) eccentric-bearings B'. Resting in said bearings is the crank-shaft C.

D is the cam-shaft, and E is the back shaft, which shafts are operated by gearing in the usual manner. The shaft E carries the cams 60 for working the heddles, and in addition thereto the cam F. G is a lever, one end of which is pivoted to the girth A' of the loom.

H is a rod connecting lever G with arm I. J is another arm, to which is secured the lock-bar K, the forward end of the latter sliding upon the lower beam, A'', of the loom.

By means of bolts and slots, as shown, the various parts may be adjusted in relation to each other for the purpose of changing the 70 grade of the fabric, as will be hereinafter more fully set forth.

Arms I and J are rigidly secured to the shaft L, and, though shown as cast in one piece, may be made separately. The lock-bar is provided 75 with projections k, to which are secured the springs M, the other ends of which are fastened to the beam A'', as shown. At each end of shaft L is rigidly secured an arm, N, which is connected with the arm O of the eccentric-bearing by means of the rod P.

Q are the pitmen which transmit motion to the lay and reed R R'.

S is the terry-lever pivoted to the breast-beam A''', and T is a bell-crank lever, also pivoted to the breast-beam at its angle T', and connected with the terry-lever S and lock-bar K by rods V in the manner shown.

The operation of the loom is as follows: Power being applied through the intervention 90 of gears in the usual manner, the various parts are brought into action. In Fig. IV, the short pin F' of cam F being clear of lever G, springs M by their tension have drawn the lock-bar K and arm J forward, giving a partial turn to 95 shaft L, and thereby imparting to arm I, rod H, and lever G an upward movement, which, as well as the said partial turn of said shaft L and the movements imparted thereby to the various parts, as hereinafter set forth, is limited by the contact of the said lever G with the abutment or stop e, Figs. III and IV, the lat-

ter in the present case being formed by the end of shaft E. The partial turn given to shaft L, as described, is also imparted, it will be evident, to arms N, and, ultimately, to each eccentric-bearing B', through the intervention of connecting mechanism O P, Fig. I, drawing the crank-shaft and the pitmen, lay, and reed to their farthest possible distance from the cloth-making line. Now, when the pin F' in its revolution comes in contact with the lever G the latter is depressed, producing by reason of the rod H a like effect upon arm I, giving a partial reverse turn to shaft L and to arm N, and this movement imparted to the eccentric-bearing B' forces the latter, and with it the crank-shaft, pitmen, lay, and reed, forward, thereby enabling the said lay and reed to reach the cloth-making line. In other words, for certain throws the lay will only partially beat up the picks of west-thread, and at others by the action of cam F drive them home, and the ratio of partial to complete beat-ups, it will be obvious, is dependent upon the number of revolutions of the crank-shaft to every revolution of cam F or shaft E, which ratio is regulated by gearing in the manner well known to those skilled in the art, from which it will appear that the cam F and the eccentric-bearing B', which it ultimately operates, may be automatically kept at rest for any desired number of beat-ups of the lay and then operated in conjunction with the crank-shaft, according as the said gearing may be varied. By this arrangement while the pin F' is clear of the lever G the crank-shaft, as has been stated, is at its farthest distance from the cloth-making line, so that for a certain number of shots of filling the lay and reed are prevented from quite reaching the said line, but at the succeeding shot, as the cam F is revolved, pin F' depresses the lever G, and with it arms I and N and rod and arm O P, giving the eccentric-bearing B' a partial turn, throwing the crank-shaft forward, and thus allowing the lay and reed to drive that and the previous shots of filling home, sliding upon the body-warp, but carrying the terry-warp with them, causing the latter to rise up from the body of the fabric and form loops on one or both sides, according as the terry-warp is drawn in the heddles. As the pin F' frees itself from the lever G, springs M by their recoil bring all the parts to their original position. These alternate operations are repeated until the looped fabric is completed and it is desired to weave a plain border. This is accomplished in the manner following: The forward end of the lock-bar K slides upon the lower beam, A'', and is partly cut away or recessed. Now, this recess would engage with the edge of the said beam were it not for the terry-lever S, which keeps the lock-bar K in an elevated position. It is evident, therefore, that by reversing the said terry-lever the lock-bar will be allowed to fall, and as the shaft L is turned by the action of the cam F, throwing the lay and reed forward to the cloth-making line, the arm J and lock-bar K will be

drawn back somewhat, so that the recessed end engages with the edge of beam A'', as shown in Fig. V, and prevents the various parts from returning. As a result the lay and reed will drive the filling home at every shot and the loom continue to weave plain cloth. This action of lever S and the parts operated thereby is accomplished without stopping the loom; and so likewise, after a sufficient amount of plain border has been woven, and it is again desired to weave the looped fabric, the lever S is merely forced to its original position, thus raising the lock bar clear of the edge of beam A'' and allowing the springs M to bring all the parts to the positions originally occupied. The loom will then continue to weave a looped fabric, as before, from which it will be seen that the loom may be made to weave a plain or looped fabric at the will of the weaver.

The length of the loop of course depends upon the stroke of the eccentric—that is, upon the distance traversed by the eccentric bearing B' in carrying the crank-shaft C from the point at which the partial beat-ups are made to the point that enables the lay and reed to reach the cloth-making line. By increasing or diminishing that distance the loop may be varied accordingly. Now, since that distance depends upon the position of the crank-shaft, and, necessarily, of the eccentric-bearing, any change in that position will vary that distance. Upon reference to Fig. IV, it will be seen that by moving the rod H in the slot of arm I in a direction from shaft L, lever G being prevented from rising by reason of the abutment or stop e, the said arm I will be somewhat depressed, giving a partial turn to said shaft L, thereby likewise depressing arm N, rod P, and arm O, and thus causing the eccentric-bearing B' to take a somewhat advanced position, carrying with it the crank-shaft. This advance in the position of crank-shaft C, it is evident, enables the lay and reed to make partial beat-ups at a point nearer the cloth-making line, and consequently lessens the length of the loops or pile in proportion. At the same time the partial turn given to shaft L by the depression of arm I throws arm J backward, and with it the lock-bar K. The latter, however, is made in two parts, x y, adjustable in the direction of its length, and may be thus lengthened sufficiently to enable it to slide upon the beam A'' and engage with the edge thereof, according as the loom is weaving looped or plain fabric, as set forth. Now, by moving the rod in the slot of arm I toward the shaft L it will be evident that the action of the parts last above described will be reversed, and that the distance of the point to which the partial beat-ups of the lay will be made from the cloth-making line will be increased and the length of the loops or pile increased accordingly, the lock-bar in this instance being shortened by the adjustment of its parts x y to correspond with the forward movement imparted to it and arm J by the partial turn of shaft L.

It will be further evident that rod H may be

adjusted in the slot of lever G for the purpose of elevating or depressing arm I, and thus varying the length of the loops or the grade of the fabric; but the slots shown in cam F, 5 arm J, and girth A' are merely for convenience in originally setting up the loom.

Having thus described our invention, what we claim as new, and desire to secure by Letters Patent, is—
10 1. In a loom for weaving looped or terry and plain fabrics, the combination, with the eccentric-journals B', having the arms O secured thereto, the rods P, arms N, shaft L, and operating mechanism for said shaft, of the crank-shaft C, pitmen Q, and the lay and reed R R', as shown and described.

15 2. The combination of cam F, lever G, rod H, arm I, shaft L, arm J, lock-bar K, springs M, eccentric-bearing B', and connecting mechanism N P O, substantially as shown and described.

20 3. The combination of cam F, shaft L, eccentric-bearing B', connecting mechanism N P O, adjustable mechanism G H I, and abutment or stop e, whereby the length of the 25

loops or grade of the fabric may be varied, substantially as shown and described.

4. The combination of terry-lever S, lock-bar K, mechanism connecting said terry-lever and lock-bar, as shown, arm J, and shaft L, substantially as shown and described. 30

5. The combination of terry-lever S, bell-crank lever T, and rods V with the lock-bar K, formed of the parts x y and adjustable in the direction of its length, and having the 35 notch a, the springs M, adjustable mechanism G J H I, shaft L, and cam F, substantially as shown and described.

6. The eccentric-bearings B' and rigidly-attached arm O, boxes B, rods P, arms N, and 40 shaft L, in combination with arms J I, rod H, adjustable lock-bar K, lever G, cam F, having pin F', stop e, the shaft E, and means for operating said shaft, substantially as shown and described.
